AIR AND FUEL SUPPLY CONTROLLING
MEANS FOR FURNACES OR THE LIKE

Homer E. Blauvelt, Flushing, N. Y.; Thelma R. Blauvelt executrix of said Homer E. Blauvelt, deceased

Application April 11, 1941, Serial No. 388,033

6 Claims. (Cl. 158—1)

This invention relates generally to air control means for oil burners, gas burners, burners using finely comminuted or powdered combustible material, etc., and more particularly refers to a regulating means for simultaneous control of primary air and secondary air supply to the burner.

It is an object of the present invention to provide efficient primary air and secondary air supply control means which are automatically regulatable according to the combustible load fed to the burner or furnace.

It is a further object of the present invention to provide simultaneous control of the primary air and secondary air supply to a burner or furnace, adjustable in accordance with a minimum and a maximum predetermined rate of fuel supply flow to give substantially perfect combustion for varying quantities of fuel supply fed to said burner up to said maximum flow.

It is yet another object of the present invention to provide a substantially uniform CO₂ content of the flue gases by regulation of the primary and secondary air admission and the fuel.

A further object of the present invention is to provide in such a burner or furnace the required proportion of primary and secondary air to the combustible fuel, to give substantially perfect combustion, and to maintain this proportion irrespective of the amount of fuel consumed.

Another object of the present invention is to provide primary and secondary air supply operating means for such a burner or furnace which means are accurately and simultaneously controlled for bringing about efficient combustion with maximum CO₂ content within the furnace.

In carrying out foregoing objects of the present invention there is provided a heating system employing a fuel burner apparatus and means for regulating the flow of fuel to said apparatus; with air admission means cooperable with said burner apparatus, rotatable means controllable by said regulating means, and means operable by said rotatable means for controlling air supply through said air admission means in accordance with the amount of fuel supplied to said apparatus for producing a desired proportion of air to fuel consumed and substantially maintaining said proportion during varying rates of flow of said consumed fuel up to a predetermined maximum rate of flow thereof.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the modifications in structure and relation contemplated by this invention, drawings depicting a certain form of the invention have been annexed as a part of this disclosure, and in such drawings, like characters of references denote corresponding parts throughout all the views, of which:

Fig. 1 is a front elevational view of a boiler with mechanism made in accordance with the invention.

Fig. 2 is a side elevational view partly in section of Fig. 1.

Fig. 3 is a sectional view taken along line 3—3 of Fig. 1 showing the pressure regulator with its connection to the operating shaft connecting the levers embodied in the invention.

Fig. 4 is a sectional view taken along line 4—4 of Fig. 1 showing the primary air inlet and adjustable connection to the operating shaft.

Fig. 5 is a cross sectional view taken along line 5—5 of Fig. 1 and showing the adjustable secondary air control and connection to an operating shaft.

Referring now to the drawings, although there is shown a fire tube boiler 10, it is understood that any other type, such as a water tube boiler, locomotive boiler, etc., may be employed, this device forming no part of the invention.

Boiler 10 is supported by the conventional foundation walls 11 forming the fire box 12 from which the flames F and hot gases enter the fire chamber 13. These flames and hot gases will heat the water 15 around the tubes 14, such flames and hot gases finally reaching the front chamber 16 and from there passing through the chimney or smoke stack 17. All this is conventional and forms no part of the invention.

On the front plate 18 of the boiler 10 is a shaft 19 rotatably mounted in bearings 20, 21. Mounted upon the front plate 22 of boiler 10 is a thermostat control or a pressure regulator 23, having an arm 24 connected by means of a connecting rod 25 and lever 26 to shaft 19 for causing shaft 19 to rotate in accordance with the pressure in the pressure regulator 23, which is determined by the pressure in boiler 10.

The movement of arm 24 will range within an arc up to about sixty degrees to ninety degrees. The burner apparatus 27 comprises the upright hollow member 28, burner member 29, and fuel line 30. A control valve 31, which controls the flow of fuel to the burner 32 is connected by means of connecting rod 33 and lever 34 to shaft 19.

Within hollow member 28 is a butterfly valve or damper 35 which controls the primary air supply to burner 29 the fuel and air mixture being burned at member 32.

The secondary air inlet 36 consists of the opening 37 located at the bottom of boiler 10 and below burner element 32. This opening 37 can be closed by a door 38, which door controls the secondary air supply entering the fire box 12. Door 38 is controlled from the rotatable shaft 19 by means of an arm 39 having an arcuate slot 40 and a sliding member 41 which can be securely clamped by conventional means within slot 40 at a predetermined position to be later described. A chain or cable 42 connects sliding member 41 to door, damper or valve 38 of secondary inlet 36. This cable 42 is guided over the fixed pulleys 43, 44, 45, respectively.

The arm 39 is provided with counterweights as shown at 53 so as to assist in balancing the weight of the damper door 38. The butterfly valve 35 is controlled from rotatable shaft 19. For this purpose an arm or lever 49 is connected to shaft 19, said lever 49 having an extension 50 provided with an arcuate slot 51. A member 52 is slideable in slot 51. An arm 46 connects with butterfly valve 35, said arm 46 having a counterweight 47 at its free end. Sliding member 52 is provided with clamping means to secure the sliding member 52 within slot 51 at a predetermined position for a purpose later on described.

Referring now more particularly to arms 39 and 49, the curvature of slot 51 is determined when the arm 49 is at its lowest position as indicated at 49', 52' by describing an arc using point 46' as a pivot and rod 48 as a radius. At this time secondary air inlet arm 39 will also be at its lowest position as indicated at 39'. Curvature of slot 40 is determined by the relation between sliding member 41 within slot 40 and the required position of the damper door 38, and swinging section 42' of cable 42 about the surface of pulley 43 when arm 39' is in its said lowest position. The furnace burner 32 at this time is receiving oil for producing the lowest practical flame. The butterfly valve 35 and damper door 38 are now adjusted by hand and secured in their adjusted positions, this position of valve 35 being indicated by 35a and the corresponding position of arm 46 by 46a, for the flame to burn the most efficient way producing a predetermined CO₂. Valve 35 is secured in its adjusted position by tightening screw 35' and door 38 is secured in its adjusted position by means of the knot K of cable 42. Regardless of position of 52 within slot 51 and of 41 within slot 40, the positions of valve 35 and door 38 will always be the same when shaft 19 brings arms 49 and 39 to their lowest positions once the locations of the respective sliding members 41 and 52 have been determined in accordance with the fuel used and the required primary and secondary air necessary for complete combustion. The oil supply to the burner is now increased to a flow of, say, eighty gallons per hour, indicating a maximum flame desirable for a particular purpose. The valve 35 and door 38 are then again adjusted, this time, however, for an air supply giving the most efficient combustion and thereby again a theoretical maximum CO₂. Slots 40 and 51 are now again marked off for positions for high fire, thereby obtaining the graduation marks 62 and 63, respectively, for high fuel consumption. For obtaining graduations or points between these and low fuel oil flows, for example, to determine the primary and secondary

air supply required for a sixty gallon per hour fuel oil flow, the above procedure is repeated. If at any future time it is desired to run the furnace with a steam production equivalent to the flow of, say forty-five gallons of fuel oil per hour, the clamping members 41, 52 of connecting cable 42 and connecting rod 48, respectively, are clamped in these positions within the slots 40, 51, marked for this fuel oil consumption, thereby repeatedly producing the most efficient combustion through the supplying of the correct amount of primary and secondary air to the fuel burner. This arrangement, in other words, will always assure the correct proportion of fuel, primary air and secondary air, thereby giving the desired predetermined CO₂, no matter how much fuel is being consumed at any particular time between the lowest practical flame and the maximum predetermined flame.

Operation

To start off a cool boiler, more oil will be required in the combustion chamber of the boiler to bring the pressure up as quickly as possible. This may require in one particular instance the consumption of eighty gallons of oil per hour. Assuming that the necessary amount of pressure has been reached within, say, one hour and one-half, it will be found that only sixty gallons of oil per hour are required to maintain the required steam pressure. The control valve 31 is now set for this oil flow and clamping members 41 and 52, which at first had been clamped to the proper location for eighty gallons of oil per hour will now be moved along the slots to the respective indicated graduations on arms 39 and 49 for sixty gallons per hour. If a change in oil supply should be desired these clamping members 41 and 52, respectively controlling the primary and secondary air supply will be adjusted accordingly. Therefore, if the pressure regulator 23 reacts on the rotating shaft 19 on account of the predetermined pressure setting, and pressure regulator 23 continuously maintains this pressure, the primary and secondary air supply to the fire box will be always such as to provide the proper proportion of air and fuel, thereby producing the most perfect combustion or, in other words, a substantially theoretical maximum CO₂.

It is obvious that since the oil supply control lever 34, the primary air supply lever 49 and the secondary air supply lever 39 are all secured to the common shaft 19, and since the shaft 19 is rotated by the action of lever 26 mounted on shaft 19, and further since lever 26 is set into motion by the action of pressure regulator 23, that all these said arms will move and operate their respective mechanisms simultaneously, and in accordance with the predetermined settings.

It is understood that although the invention has been described with reference to oil burners, the aforementioned primary and secondary air control mechanisms may be employed in connection with furnaces or boilers using other fuels, such as for example, natural or illuminating gas, pulverized coal, etc. and where an efficient air supply control is required.

Although the drawings and the above specification disclose the best mode in which I have contemplated embodying my invention, I desire in no way to be limited to the details of such disclosure, for in the further practical application of my invention many changes in the forms and proportions may be made as circumstances

require or experience suggests without departing from the spirit of the invention within the scope of the appended claims.

Having thus described the invention what is claimed as new and desired to be secured by Letters Patent, is:

1. In combination with a heating apparatus having a front plate, a fuel burner and means for supplying fuel to said burner; means for controlling the supply of fuel to said burner, said means including spaced bearings fixed to said plate, a rotatable shaft mounted in said bearings, means for admitting primary air to said apparatus, means for admitting secondary air to said apparatus, means for controlling the quantity of primary air to said apparatus, means for controlling the quantity of secondary air to said apparatus; one of said air controlling means comprising a member fixed to said shaft mounted in said bearings to rotate therewith, said member having a curved slot, a valve device for one of said air admitting means, an arm connected at one end to said device and having a weight adjacent its other end, a link pivotally connected at one end to said arm between said weight and said device, and a member at the other end of said link slidable in said slot; the other of said air controlling means comprising a member fixed to said shaft mounted in said bearings to rotate therewith, said last mentioned member having a curved slot, a movable damper device for the other of said air admitting means, a flexible connection, one end of said connection being secured to said last mentioned device, and a member fixed to the other end of said connection and slidable in said last mentioned slot.

2. In combination with a heating apparatus having a front plate, a fuel burner and means for supplying fuel to said burner; means for controlling the supply of fuel to said burner, said means including spaced bearings fixed to said plate, a rotatable shaft mounted in said bearings, means for admitting primary air to said apparatus, means for admitting secondary air to said apparatus, means for controlling the quantity of primary air to said apparatus, means for controlling the quantity of secondary air to said apparatus; one of said air controlling means comprising a member fixed to said shaft to rotate therewith, said member having a curved slot, a valve device for one of said air admitting means, an arm connected at one end to said device and having a weight adjacent its other end, a link pivotally connected at one end to said arm between said weight and said device, and a member at the other end of said link slidable in said slot.

3. In combination with a heating apparatus having a front plate, a fuel burner and means for supplying fuel to said burner; means for controlling the supply of fuel to said burner, said means including spaced bearings fixed to said plate, a rotatable shaft mounted in said bearings, means for admitting primary air to said apparatus, means for admitting secondary air to said apparatus, means for controlling the quantity of primary air to said apparatus, means for controlling the quantity of secondary air to said apparatus, one of said air controlling means com-

prising a member fixed to said shaft, said member having a curved slot, a valve device for one of said air admitting means, a flexible connection, one end of said connection being secured to said device, and a member fixed to the other end of said connection and slidable in said slot.

4. In combination with a heating apparatus having a front plate, a fuel burner and means for supplying fuel to said burner; means for controlling the supply of fuel to said burner, said means including spaced bearings fixed to said plate, a rotatable shaft mounted in said bearings, means for admitting primary air to said apparatus, means for admitting secondary air to said apparatus, means for controlling the quantity of primary air to said apparatus, means for controlling the quantity of secondary air to said apparatus, one of said air controlling means comprising an arm fixed to said shaft to rotate therewith, said arm having a curved slot, a valve device at one of said air admitting means, and connecting means between said device and said arm, said connecting means including a member slidable in said slot; the other of said air controlling means comprising a member fixed to said shaft, said latter member having a curved slot, a valve device at the other of said air admitting means, a connection having one end secured to said latter mentioned device and its other end secured in the said last mentioned slot.

5. In combination with a heating apparatus having a front plate, a fuel burner and means for supplying fuel to said burner; means for controlling the supply of fuel to said burner, said means including spaced bearings fixed to said plate, a rotatable shaft mounted in said bearings, means for admitting primary air to said apparatus, means for admitting secondary air to said apparatus, means for controlling the quantity of primary air to said apparatus, means for controlling the quantity of secondary air to said apparatus; each of said air controlling means comprising a movable damper device for the respective air admitting means, an arm fixed to said shaft to rotate therewith, said arm having a curved slot, and means connecting each of said damper devices with said arm, said connecting means having a part slidable in said slot.

6. In combination with a heating apparatus having a front plate, a fuel burner and means for supplying fuel to said burner; means for controlling the supply of fuel to said burner, said means including spaced bearings fixed to said plate, a rotatable shaft mounted in said bearings, means for admitting primary air to said apparatus, means for admitting secondary air to said apparatus, means for controlling the quantity of primary air to said apparatus, means for controlling the amount of secondary air to said apparatus; each of said air controlling means comprising a movable damper device at the respective air admitting means, an arm fixed to said shaft to rotate therewith, said arm having a curved slot, and means connecting said device with said arm, said connecting means having a part slidable in said slot.

HOMER E. BLAUVELT.
